CLAIM

The ornamental design for a sensor of radiologic apparatus for use in the mouth, as shown and described.

DESCRIPTION

FIG. 1 is a front elevational view of a sensor of radiologic apparatus for use in the mouth showing our new design;

FIG. 2 is a top view thereof;

FIG. 3 is a rear elevational view thereof;

FIG. 4 is a left side elevational view thereof, the right side being a mirror image; and,

FIG. 5 is a bottom plan view thereof.
